(57) **CLAIM**

The ornamental design for a golf club head, as shown and described.

DESCRIPTION

FIG. 1 is a front view thereof;

FIG. 2 is a top plan view thereof;

FIG. 3 is a bottom plan view thereof;

FIG. 4 is a rear perspective view thereof;

FIG. 5 is a heel view thereof; and,

FIG. 6 is a toe view thereof.

The broken line showing is for illustrative purposes only and forms no part of the claimed design.
